ISAAC B. HYMER, OF WARSAW, INDIANA.

Letters Patent No. 63,640, dated April 9, 1867.

IMPROVED RAILROAD RAIL.

The Schedule referred to in these Letters Patent and making part of the same.

TO ALL WHOM IT MAY CONCERN:

Be it known that I, ISAAC B. HYMER, of Warsaw, in the county of Kosciusko, and State of Indiana, have invented a new and improved Railroad Rail; and I do hereby declare the following to be a full, clear, and exact description of the same, sufficient to enable one skilled in the art to which the invention appertains to make use of it, reference being had to the accompanying drawings, which form a part of this specification, and in which—

Figure 1 is a perspective view.

Figure 2 is a transverse vertical section.

This rail is compounded of four pieces, of which one forms the base and the central supporting flange, which is embraced by two side pieces, whose upper portions form a dove-tailed socket for the flange underneath the upper cast-steel track rail.

In the drawings, A is a portion whose transverse section resembles an inverted T, thus: A. Its foot with lateral flanges forms the support of the rail, and its upward portion is embraced between two pieces, B B, which are bolted through and through by the bolts and nuts C C. At the upper part of these side pieces are dove-tailed notches, which together form a socket to contain the lower flange d of the upper cast-steel rail D which forms the track. This upper portion may be removed as often as occasion may require, and the various portions may be so attached as to break joints, not having any two joints occur in the same point in the length of the combined rail. The pieces A B B are made of iron, and are not subjected to wear. The bolt-holes will be somewhat oblong to admit of expansion and contraction.

Having described my invention, what I claim therein as new, and desire to secure by Letters Patent, is—

I claim the rail D, having a dove-tailed tenon clasped between the side plates B B, which are supported against and upon the bed rail A, substantially as described and represented.

ISAAC B. HYMER.
